UNITED STATES PATENT OFFICE.

RICHARD A. WHITTINGHAM, OF NEWARK, DELAWARE.

RAILWAY-TRACK STRUCTURE.

Application filed October 23, 1924. Serial No. 745,466.

This invention relates to a railway track structure whereby the heads of the track rails are continuously supported by stringers, and these stringers are so designed that 5 they may rest directly upon the ballast and give the necessary support to the rails without the use of cross-ties. The stringer of my invention is composed of rolled steel plates arranged at opposite sides of the track 10 rail and supporting the same, each plate comprising a flat bearing portion, of substantial width, adapted to rest upon the ballast, a flanged portion extending upwardly from one edge of the bearing portion and 15 adapted to engage the underside of the head of the track rail, to support the same, and a web portion extending downwardly from the bearing portion, the webs of the opposing plates being adapted to extend deeply 20 into the ballast and prevent lateral displacement of the track.

The stringer plates are secured together and to the rail by bolts passing through the flanges of the plates and the webs of 25 the rails. The webs of the plates are not secured to one another, but are engaged at their lower parts by clamps or yokes which allow the plates to be rocked apart, to permit of the insertion or removal of a rail, 30 when the bolts are removed from the flanges. Thus, the fastening devices for the stringers are all above the roadbed, where they are accessible at all times.

At suitable intervals in the length of the 35 track, ties are employed to connect together the stringers which support the opposing rails of the track, and these ties are formed so as to engage the bearing portions and the webs of the stringers and to hold the 40 stringers and the rails at the proper gage while the ballast is being tamped under the stringers. These ties are secured to the stringers by fastening devices which are accessible from the surface of the roadbed.

45 In the accompanying drawing,

Fig. 1 is a plan view of a portion of a railway track embodying my invention;

50 Fig. 2 is a transverse section through the track and roadbed, the rails and stringers being shown in perspective;

Fig. 3 is a perspective view showing one side of one of the stringer plates;

Fig. 4 is a similar view showing the other side of one of said plates; and

55 Fig. 5 is a section through a modified form of track structure.

Referring to Figs. 1-4 of the drawing, *a* represents a ballasted railway roadbed, *b* indicates the rolled metal plates composing the stringers, *c* represents the track rails, 60 and cross-rods or ties are shown at *d*, for maintaining the alinement and gage of the track while the ballast is being tamped under the stringers during construction, or af- 65

Each stringer is composed of the opposing steel plates *b*—*b*, of similar form in cross section, and the plates are of such form that they may be readily manufactured by rolling. As shown, each plate comprises a 70 flat, relatively wide, bearing portion *1*, adapted to rest directly on the ballast, and having an upstanding flange *2*, at one edge, which is of the form and height of an ordinary splice-bar. This flange is adapted 75 to engage the under side of the rail head to support the same, and the flanges of the opposing plates are bolted together through the web of the rail by bolts *e*, which hold the flanges firmly against the rail. The 80 web portion *3* extends downwardly from the under side of the bearing portion along a line on the latter which is intermediate its edges, as shown at *3*^a, thence extending laterally, as shown at *3*^b, to a point beneath 85 the track rail, thence extending horizontally outward in the form of a foot or flange, as shown at *3*^c. The parts *3*^a, *3*^b, of the opposing plates and the bearing portions above them form a channel *f*, below the bearing portion, wide enough to receive the base of an ordinary track rail. In the drawing, a double-headed rail is shown, one head being within the channel, and when the upper head is worn, the rail may be reversed to 90 bring the lower head into use. Obviously, rails consisting merely of heads and webs may be used with the stringers; but the channel below the bearing portions of the stringer is provided for receiving the heads 100 of double-headed rails or the bases of T-rails, when such are used.

The plates comprising the stringers are of the same lengths as the rails, and in laying the track the plates composing the 105 stringer are arranged so that the joints between the successive plates on one side of a stringer will be between the joints of the successive plates composing the other side of the stringer, and also so that the joints 110 between successive rails will not occur at the joints between successive plates of a stringer.

Thus, the rail heads will have continuous support at the joints.

At suitable intervals, the stringers which support the two rails of a track are connected by metal ties *d*, having at each end a yoke *d'* which extends beneath the stringer and has its outer end 4 bent over to form a sort of hook for engaging the edge of the bearing portion of the outer stringer plate, 10 as shown. Clips 5, removably secured to the ties, are adapted to engage the inner edges of the bearing portions of the inner stringer plates. The central parts of the yoke *d'* are formed so as to fit rather closely around the feet 3^a of the stringer plates. 15 These yokes prevent the webs from spreading under pressure of the load. The tie, as shown in the drawing, is composed of two parts connected by an insulating fitting 6, of standard form, which need not be described. These fittings are commonly used where it is necessary to keep the track rails electrically insulated from one another. The ties *d* are preferably placed at points where 20 a joint occurs in the stringer plates. The chief function of the tie is to maintain the track rails at the proper gage while the ballast is being tamped under the stringers, either during construction, or afterwards. 25 The bearing portions of the stringers extend outwardly for a distance of about 7" from the central plane of the track rail, at opposite sides of the latter, and the structure is supported directly by the ballast 30 which is tamped under the bearing portions and under the horizontal portions 3^b of the webs and under the lower flanges 3^a. The webs extend rather deeply into the ballast and prevent any lateral displacement of the 35 structure.

It will be seen from the foregoing that the stringer structure described provides a continuous rigid support for the track rails, which prevents breakage of the rails, and 40 that the structure has ample bearing surface on the ballast to support the rails, without the usual wooden cross-ties or sleepers. It will also be evident that any usual form of railway rail may be supported by the stringer structure and that the plates of the stringer structure are of 45 such form that they can be made by the rolling process, which is important from a manufacturing standpoint.

50 The only fastening devices required to hold the stringer plates together and to the track rail are the track bolts which pass through the flanges of the plates and the web of the rail. When these and the clips 55 are removed, the plates may be moved relatively to one another, since the webs of the plates are not fastened together, but are merely held from spreading by the yokes or clamps. By jacking up the stringer plates 60 from the bottom, the plates may be rocked

apart to remove or insert rails. Thus, all of the fastening devices which must be removed or replaced, to remove or replace a rail, are accessible without the necessity of going beneath the surface of the ballast. 70

In Fig. 5, the structure is the same as in the previously described figures, except that the webs 3^c of the plates are flat and in line with the flanges 2^a. This form of plate is desirable where the rail *c'* consists 75 merely of a head and web, as shown.

What I claim is:

1. A railway track structure comprising a rail and a stringer, the latter composed of similar reversely-arranged plates, each plate having a relatively wide bearing portion adapted to rest upon the roadbed and projecting laterally for a considerable distance beyond the bottom of the rail, a flange projecting upwardly from the bearing portion at the side of the web of the rail, and a web extending below the bearing portion. 85

2. A railway track structure comprising a rail and a stringer, the latter composed of similar reversely arranged plates, each plate having a relatively wide bearing portion adapted to rest upon the roadbed and projecting laterally for a considerable distance beyond the bottom of the rail, a flange projecting upwardly from the inner edge of 90 the bearing portion and a web extending below the bearing portion, said rail being supported by and between said flanges. 95

3. A railway track structure comprising a rail and a stringer, the latter composed of similar reversely arranged plates, each plate having a relatively wide bearing portion adapted to rest upon the roadbed and projecting laterally for a considerable distance beyond the bottom of the rail, a flange 100 projecting upwardly from the inner edge of the bearing portion and a web extending below the bearing portion, said rail having a head supported on said flanges and a web bolted between said flanges. 105

4. A railway track structure comprising a rail and a stringer, the latter composed of similar reversely arranged plates, each plate having a relatively wide bearing portion adapted to rest upon the roadbed and projecting laterally for a considerable distance beyond the bottom of the rail, a flange 110 projecting upwardly from the inner edge of the bearing portion and a web extending below the bearing portion, said rail being supported by and between said flanges, and means engaging said webs and preventing their lateral separation. 115

5. A railway track structure comprising a rail and a stringer, the latter composed of 120 similar reversely arranged plates, each plate having a relatively wide bearing portion adapted to rest upon the roadbed and projecting laterally for a considerable distance beyond the bottom of the rail, a flange 125 pro-

jecting upwardly from the inner edge of the bearing portion and a web extending below the bearing portion, said rail being supported by and between said flanges, and means engaging said webs and separable therefrom, for preventing the lateral separation of the webs.

6. A railway track structure comprising a rail and a stringer, the latter composed of 10 similar reversely arranged plates, each plate having a relatively wide bearing portion adapted to rest upon the roadbed and projecting laterally for a considerable distance beyond the bottom of the rail, a flange projecting upwardly from the inner edge of the bearing portion and a web extending below the bearing portion, said rail being supported by and between said flanges, and a yoke fitting around the lower edges of said webs.

15 7. A railway track structure comprising a rail and a stringer, the latter comprising two similar reversely arranged plates each having a relatively wide bearing portion adapted to rest upon the roadbed and projecting laterally for a considerable distance beyond the bottom of the rail, a flange projecting upwardly from the inner edge of the bearing portion and fitting against the web and beneath the head of the rail and a web 20 extending downwardly from the bearing portion, the webs of both plates lying adjacent one another in the plane of the rail, and bolts extending through said flanges and the web of the rail, said plates being separately 25 movable when said bolts are removed.

8. A railway track structure comprising parallel rails and stringers supporting the rails, each stringer comprising two similar reversely arranged plates, each plate having 30 a relatively wide bearing portion adapted to rest upon the roadbed and having a flange projecting upwardly from the bearing portion and fitting against the web of the rail and having a web extending downwardly 35 from the bearing portion, and bolts extending through said flanges and the web of the rail, in combination with yokes, each having a central portion fitting around the lower parts of the plates of a stringer and detachably secured at its ends to the bearing 40 portions of said plates, and means connecting the yokes on the opposing stringers of the track structure.

9. A railway stringer plate comprising a 45 substantially flat bearing portion, an upstanding flange at one edge thereof adapted to engage the head of a track rail and a web portion extending downwardly from the

bearing portion along a line spaced from 50 said flange, thence extending laterally under the flange, and thence downwardly.

10. A railway stringer plate comprising a substantially flat bearing portion, an upstanding flange at one edge thereof adapted to engage the head of a track rail and a web 55 portion extending downwardly from the bearing portion along a line spaced from said flange, thence extending laterally under the flange, thence downwardly, and thence laterally in the opposite direction. 70

11. A railway stringer plate comprising a substantially flat bearing portion, an upstanding flange at one edge thereof adapted to engage the head of a track rail and a web 75 portion extending downwardly from the bearing portion along a line spaced from said flange, thence extending laterally below and beyond the flange, and thence downwardly.

12. A railway stringer plate comprising 80 a substantially flat bearing portion, an upstanding flange at one edge thereof adapted to engage the head of a track rail and a web portion extending downwardly from the bearing portion along a line spaced from 85 said flange, thence extending laterally below and beyond the flange, thence downwardly, and thence laterally in the opposite direction.

13. A railway stringer comprising two 90 similar opposed plates, each plate having a substantially flat bearing portion, an upstanding flange at one edge thereof adapted to engage the head of a track rail and having a web portion extending downwardly 95 from the bearing portion along a line spaced from said flange, thence extending laterally, beneath the flange, toward the opposing plate and thence downwardly.

14. The combination with a railway rail 100 of a stringer comprising two similar reversely arranged plates disposed at opposite sides of the rail, each plate having a substantially flat bearing portion adapted to rest upon the roadbed, an upright flange fitting under the head of the rail, and a web portion extending downwardly from the bearing portion along a line spaced from said flange, thence laterally beneath the track rail and thence downwardly, and bolts passing through said flanges and the web of the track rail. 110

In testimony whereof I hereunto affix my signature.

RICHARD A. WHITTINGHAM.
